[57] **ABSTRACT**

In a device for inspecting watch movements, a piezoelectric contact microphone is supported for engagement with the stem of a watch movement which is urged into axial engagement with the piezoelectric element of the microphone to transmit the vibrations of the watch movement to the element whereby the compressive stresses applied thereto are varied and an output voltage is produced which is adapted to be used in examining the accuracy of the watch movement.

PIEZOELECTRIC MICROPHONE

This invention relates to apparatus for inspecting watch movements, and more particularly to piezoelectric contact microphones for use in such apparatus which are operatively connected to the watch movement to receive the vibrations thereof and produce an output voltage which is adapted to be used in examining the accuracy of the movement.

Apparatus of the above type has been proposed in the past which includes a sound microphone and a sound pick up device such as a crystal or piezoelectric microphone which is adapted to transform the mechanical vibrations of the watch movement, caused by the release, drive and dropping impacts of the escapement mechanism, into electrical vibrations and an output voltage which is utilized in examining the accuracy of the movement. Transformation of watch vibrations into electrical output voltage by a piezoelectric crystal has been effected in a variety of ways, the most common of which consists in operatively connecting the crystal to the watch movement in a position such that the crystal will be vibrated in flexure to produce the deformation of the piezoelectric crystal element and thereby generate a varying output voltage between the faces of the element.

It has generally been found that in order to obtain maximum sensitivity of piezoelectric microphones which operate in flexure, as described above, the crystal used in the microphone must be selected in such a manner that its resonant frequency is within the frequency spectrum of the vibrations generated by the watch movements being inspected. The frequency of these vibrations is generally within a range of between 5 and 20 kilocycles, and the crystals are therefore chosen in accordance with this range. However, a major difficulty arises with apparatus utilizing piezoelectric crystals of this type in that the frequency range is excessively selective and numerous watch movements having vibration frequencies outside this range cannot be inspected using this type of crystal. To inspect watch movements which have a vibration frequency spectrum outside the range of the piezoelectric element chosen, it has been proposed that an element having a larger resonant frequency, which encompasses the frequency spectrum of the mechanical vibrations of these watch movements, be provided; however, it has been found that the sensitivity of systems using such crystals is severely effected, even to the extent of rendering the system impractical for use, since the signal-to-noise ratio of such crystals approaches 1 as their resonant frequency increases.

Accordingly, it is an object of the present invention to examine watch movements with a piezoelectric microphone and to attain a high signal-to-noise ratio.

It is a further object of the invention to examine watch movements having a wide vibration frequency spectrum with a piezoelectric contact microphone having a relatively high signal-to-noise ratio.

Another object of the invention is to provide a device for the inspection of watch movements which is both economical and simple in construction.

In accordance with an aspect of the present invention, an apparatus for inspecting watch movements includes a piezoelectric element mounted for operation in compression between a support member on the ap-

paratus and the stem of a watch movement. It has been found that by thus positioning a piezoelectric element for operation in compression its resonant frequency is placed outside the frequency spectrum of the vibrations of watch movements while at the same time its sensitivity is maintained or increased. In addition, the piezoelectric microphone is connected to a pre-amplifier, as for example an integrated circuit amplifier, which is adapted to match the impedance of the piezoelectric element to the impedance of the line and thus substantially improve sensitivity and accuracy of the watch movement inspection apparatus. Moreover, the pre-amplifier will amplify the electric signal produced by the element to a level, which for example may be approximately one volt peak to peak, sufficient to decrease the effects of noise in the transmission line on the output of the piezoelectric element. The use of an intermediate pre-amplifier also avoids a direct electric coupling between the output of the piezoelectric element and the input of the amplifier used in the inspection apparatus because the gain and input impedance of the inspection apparatus is thereby substantially reduced.

The above, and other objects, features and advantages of this invention, will be apparent in the following detailed description of illustrative embodiments thereof which are to be read in connection with the accompanying drawings, wherein:

FIG. 1 is a schematic illustration of the principal of operation of the present invention;

FIG. 2 is a schematic illustration of an embodiment of the present invention;

FIG. 3 is a schematic illustration similar to FIG. 2 of another embodiment of the present invention;

FIG. 4 is an elevational view, with parts broken away, of a device of a type in which the present invention may be employed; and

FIG. 5 is a sectional view of the support housing for the piezoelectric microphone utilized in the embodiment of the invention illustrated in FIG. 4.

Referring now to the drawings in detail, and initially to FIGS. 1 and 2 thereof, it will be seen that a piezoelectric element 10 of the type used in conjunction with the present invention is held, in accordance with the present invention, in axial compression against a support member 12 by a force 14, which is, in one embodiment, applied by direct contact with a watch movement 16. The amplitude of force 14 varies in accordance with the vibrations of the watch movement as caused by the release drive and dropping impacts of the escapement mechanisms and when applied to element 10, the force vibrates the element in compression and causes the piezoelectric element to generate a varying electrostatic voltage between the opposed faces 18 and 20 of the element. The opposed element faces 18 and 20 are connected by output leads 22 for transmission of the voltage signal to a device (not shown) which utilizes the voltage to determine the accuracy of the watch movement 16 being tested. By positioning element 10 for operation in compression in this manner, it is adapted to vibrate within a relatively large frequency range to accommodate a wide range of watch movements having varying vibration frequency spectrums in order to facilitate inspection of numerous types of watch movements.

Piezoelectric element 10 is formed of a ceramic material, as for example, barium titanate. This material is not particularly sensitive to temperature variations in the normal temperature range at which the inspection apparatus is normally used. As a result the inspection apparatus of the present invention gives highly accurate readings as compared to the previously proposed devices using crystal piezoelectric elements. Further, element 10 is formed as an elongated cylindrical member. This configuration provides a high degree of sensitivity when the device is operating in compression.

As illustrated schematically in FIG. 2, the force 14 is applied to compress element 10 by direct contact with stem 24 of watch movement 16. Stem 24 is urged axially against element 10 by compression spring 26 which is operatively engaged at its ends between a support member 28 and crown 25.

As seen in FIG. 3, compressive force 14 may be applied to piezoelectric element 10 indirectly by a lever mechanism 30 which is operatively engaged between crown 25 of watch movement 16 and element 10. In this embodiment lever 30 is pivotally mounted at 32 on a support member 34 and has a first end 36 operatively engaged with end 20 of element 10 and a second, opposed, end 38 in contact with crown 25. As in the previously described embodiment, resilient compression spring 26 is operatively engaged between support member 28 and crown 25; in this embodiment, however, spring 26 urges stem 24 and crown 25 against lever end 38. In this manner, lever end 36 is moved into engagement with face 20 of element 10 to compress the element against support portion 12 and thereby transmit vibrations of the watch movement to element 10 in an axial direction to vary the compressive forces applied thereto.

It is noted that in the embodiment illustrated in FIG. 3 lever 30 may be utilized in accordance with the location of pivot point 32 to amplify or decrease the vibrations produced by watch movement 16 prior to transmission thereof to element 10.

In each of the embodiments described above, leads 22 are respectively connected at their opposed ends to pre-amplifier 40, which may, for example be formed as an integrated circuit amplifier. Amplifier 40 receives the output voltage produced across the faces of element 10 and serves to match the impedance of the piezoelectric element to the impedance of the output lines 42. Lines 42 are connected in the conventional manner to an inspection apparatus (not shown) which is utilized in examining the accuracy of the watch movement. Pre-amplifier 40 also serves to amplify the electric signal produced by the piezoelectric element to a level of about 1 volt, peak to peak, to decrease the effects of noise in transmission line 42 on the output of element 10, and moreover, avoids a direct electric coupling between element 10 and the amplifier used in the inspection apparatus itself whereby the gain in the input impedance of the latter may be substantially reduced.

A detailed illustration of a watch support mechanism 50, adapted for use in conjunction with the present invention, is shown in FIG. 4 wherein a support platform or base 52 is provided for watch movement 16 which includes a housing 54 containing piezoelectric element 10. Watch movement 16 is seated on a slide member 56

adapted to move laterally within support member 52 and urged towards the left in FIG. 4 by spring 26 which acts in compression between abutment surface 58 of element 56 and wall portion 12 of support platform 52. 5 Slide 56 includes an abutment member 60 which engages watch crown 24 and, by its rigid construction with slide 56, cooperates with spring 26 to urge watch movement 16 against housing 54 and piezoelectric element 10, as will be more fully described hereinafter. A finger piece 62 is provided on slide 56 to facilitate movement of watch movement 16 away from housing 54 in order to remove the watch from the device.

Housing 54 for piezoelectric element 10 is more clearly illustrated in FIG. 5, wherein it is seen that the housing includes a wall portion 64 rigidly attached to support platform 52. Piezoelectric element 10, which is provided with conductive supporting caps 66 and 68 fixed at its ends 18 and 20 respectively, is rigidly held at 15 end 18 by engagement of cap 66 with abutment members 70 contained within support wall 64. Housing 54 is completed by a second support wall 72 which encloses element 10 and includes an inner annular bore 74. As seen in FIG. 5, an annular ring 76 is seated within bore 25 74 against surface 78 of member 64. Support wall 72 includes an annular flange 80 enclosing one end of bore 74 opposite watch movement 16 and defines an aperture 81 through which a contact piece 82 extends for engagement with the winding stem 24 of watch movement 16. Contact piece 82 receives end 20 of element 10 and supporting caps 68 therein whereby the vibratory forces from watch movement 16 are transmitted directly to piezoelectric element 10. Member 82 includes an annular flange portion 84 which is retained 30 between a pair of annular rubber rings 86 and 88, which permit movement of contact piece 10 with respect to support portion 72. As seen in FIG. 5, ring 86 is engaged between flange 84 and surface 90 of ring 76 to limit the movement of contact piece 82 and ring 35 88 is engaged between flange 84 and flange 80 to further limit movement of contact piece 82 and also provide support therefore in the manner illustrated. Rings 86 and 88 serve to isolate vibrations transmitted 40 through contact piece 82 from the ring 76 and frame member 72 during transmission to element 10 to assure their complete transmission to the piezoelectric element through metal supporting caps 66 and 68. These caps provide electrical connection between the ends 18 45 and 20 of element 10 and wires 22, which in turn are connected to pre-amplifier 40 to transmit the varying voltages produced by vibration of element 10. As seen in the drawings, one of the wires 42 leading from pre-amplifier 40 is connected to support platform 52 as a 50 ground lead, whereas the other lead extends through the housing to a point of connection with the inspection apparatus.

By placing stem 24 of watch movement 16 in direct engagement with element 10 vibrations from within the 55 watch movement are directly transmitted to the element. As a result the resolution of these vibrations is increased, i.e., the vibrations produced by the various impacts in the escape mechanism can be distinguished more easily and the signal produced by element 10 contains more detail.

It is thus seen that a relatively simple apparatus has been provided for use in determining the accuracy of a

variety of watch movements. Construction of apparatus in accordance with the present invention facilitates the use of a piezoelectric element, which is held in compression to increase the relative frequency spectrum thereof in order to permit inspection and testing of a large range of watch movements.

Although illustrative embodiments of the present invention have been described herein with reference to the accompanying drawings, it is to be understood that the invention is not limited to those precise embodiments, and the various changes and modifications may be effected therein by one skilled in the art without departing from the scope or spirit of this invention.

What is claimed is:

1. A device for inspecting watch movements having operating stems, said device comprising a base for supporting a watch movement in a relatively fixed position, a piezoelectric element having first and second end portions and adapted to produce an output voltage when vibrated in compression along the axis between said ends, a rigid support member engaging said first end portion of said piezoelectric element and holding said first end portion in a relatively fixed position against axial movement thereof, means operatively engaged between a watch movement on said base and said second end portion of said element for holding said element in compression against said rigid support member and for transmitting vibrations from said watch movement to said element to thereby vary the compressive stresses against said element, and resilient means urging said watch into contact with said means operatively engaged between said watch movement and said second end portion of said element, whereby said element produces an output signal representative of said vibrations.

2. A device as defined in claim 1 including a pre-amplifier operatively connected to said piezoelectric element.

3. A device as defined in claim 1 wherein said piezoelectric element is formed of a ceramic material.

4. A device as defined in claim 3 wherein said ceramic material is barium titanate.

5. A device as defined in claim 3 wherein said element is formed as an elongated cylindrical member.

6. A device as defined in claim 1 wherein said means operatively engaged between said watch movement

and said piezoelectric element is positioned to contact the stem of a watch movement placed on said base whereby vibrations in said watch movement are transmitted directly through said stem to said crystal.

5 7. A device as defined in claim 6 wherein said resilient means comprises a compression spring operatively engaged between the crown of said watch movement and a portion of said base.

8. A device as defined in claim 1 wherein said means 10 operatively engaged between said watch movement and said second end portion of said piezoelectric element includes a pivotally mounted arm member operatively engaged between said second end portion of the element and the watch movement, said resilient means 15 being positioned to urge said watch movement into contact with said arm member to pivot said arm and compress said piezoelectric element, whereby vibrations of said watch movement are transmitted to said element through pivotal movements of said arm member.

20 9. A device as defined in claim 8 wherein said resilient means comprises a compression spring operatively engaged between said watch movement and a portion of said base.

25 10. A device as defined in claim 1 including a housing mounted on said base member, with said rigid support member forming one wall of said housing and said element being contained therein, said means for transmitting vibrations comprising a contact member 30 slidably mounted in said housing and having one end engaged with said second end portion of said element and the opposite end thereof positioned to engage the stem of the watch movement.

35 11. A device as defined in claim 10 wherein said other end of said contact member is recessed to receive said watch stem.

12. A device as defined in claim 11 wherein said contact member is generally cylindrical and has an annular flange formed thereon adjacent said one end thereof, said housing including a first resilient ring surrounding 40 said contact member adjacent said flange and a second resilient ring surrounding said element on the other side of said flange to isolate vibrations transmitted through said contact member from said housing and assure their transmission to said element.
